UNITED STATES PATENT OFFICE

FRANK D. ROBBINS, OF NEWBERG, OREGON

DRIER

Application filed September 25, 1929. Serial No. 395,036.

My invention is intended as a drier and is primarily intended for the drying of fruits, nuts, vegetables and other farm products.

The invention consists primarily of a furnace, a plurality of sloping tray supports and means for predetermining the rate and velocity of flow of heated air through the furnace and through the column of trays. The heating unit is composed of spaced heads secured to a drum and having a plurality of flues in spaced relationship secured to the head upon their oppositely disposed end. The flues are disposed in spaced relationship with the inner surface of the drum and with each other. Means are also provided for the induction of the air through the furnace and through the heat chamber in which the trays are placed and means are also provided for dampening the flow or regulating the flow within the respective trays and tray chambers.

The primary object of my invention is to provide means for generating heat within the heat chamber that will develop and utilize practically all of the heat contained within the fuel being used and that will deliver the same within the drying chamber.

A further object of my invention consists in providing a drier of but few parts, one that is relatively cheap in first cost and one that may be used over relatively long operating periods with a minimum of mechanical expense.

With these and incidental objects in view, the invention consists in certain novel features of construction and combination of parts, the essential elements of which are set forth in the appended claim, and a preferred form of embodiment of which is hereinafter shown with reference to the drawings which accompany and form a part of this specification.

In the drawings:

Fig. 1 is a vertical, longitudinal, sectional view of the assembled device.

Fig. 2 is a fragmentary, top, plan view of the breeching leading from the drying chamber. The same is made to illustrate the induction fans disposed within the breeching.

Fig. 3 is a vertical, sectional, end view of the fans disposed within the heating chamber, the same being taken on line 3—3 of Fig. 1 looking in the direction indicated.

Fig. 4 is a vertical, sectional, side view of the furnace, the same being taken on line 4—4 of Fig. 3 looking in the direction indicated.

Fig. 5 is a front view of the furnace and of the fire door hingedly secured thereto.

Fig. 6 is a fragmentary, sectional, end view of a portion of the tray stacks disposed within the drying chamber.

Fig. 7 is a perspective, front view of a roll for regulating the flow of air through the drying chamber the same being adapted for being wound about a roller and having spaced holes disposed therein through which the air passes, the same to act as a damper.

Like reference characters refer to like parts throughout the several views.

1 is the outer drum or jacket of the heating furnace having spaced heads 2 and 3 and having a fire door 4 disposed in the outer end of the furnace. A central opening 5 is disposed within the heat 2 of the furnace to 75 which a smoke pipe 6 is secured. The smoke pipe preferably has several turns or returns disposed within the heat chamber 7 in order that the heat may be extracted from the smoke pipe and that the same will be eliminated within the heat chamber to make the liberated heat available for drying purposes.

A plurality of flues 8 are secured upon their oppositely disposed ends to the respective heads of the furnace, the same being in spaced relationship with the inner surface of the jacket and being in spaced relationship with each other. The bottom flues 9 of the series rest upon grate bars 10 and the fuel for gen-

erating heat within the furnace rests directly upon the bottom flues. The grates 10 are disposed immediately therebelow to prevent a sagging or dropping down of the flues when the same become overheated. The products of combustion drop through the grate bars into the ash pit below. A drying chamber 15 is disposed above the heat chamber and the heat flows from the heat chamber through the 10 drying chamber into the breeching 14. Induction fans 13 are disposed within the breeching for inducing the flow of heated air through the furnace and the drying chamber. The trays are composed of side and end walls 15 with a screen 16 secured in place and the trays are placed within the drying chamber and rest upon guide bars 17 and 18. Baffle bars 19 and 20 are disposed immediately beneath the screen 16 and normally prevent the sagging of the screen after the same has been used for a short time. The sagging of the screen causes the article to be dried to gravitate substantially to the center and pile up in the center and the purpose of the baffles 19 25 and 20 is to prevent the sagging and at the same time to force the air for drying purposes to pass through the central mass to be dried that is disposed upon the screen. An entrance door 21 is provided at the front of 30 the inclined surface and a removable door is disposed at the oppositely disposed end of the furnace. To prevent the free flowing of the air through the drying chamber, I have found that splendid results are obtained by 35 the placing of a roller 23 within the end of the breeching and at the upper inclined end of the drying chamber and I secure a fabric to the roller that may be rolled about the roller. Spaced holes 24 are disposed within 40 the fabric. There is a tendency for the air to flow more freely through one portion of the drying chamber than through other portions of the same and this is corrected by placing holes of different sizes within the 45 fabric screen thereby dampening the flow in certain parts and increasing it in others by predetermining the amount of opening through which the same flows. The purpose of the fabric screen is to act as a regulatory 50 damper for limiting the free flowing of air through the drying chamber. A common actuator 24A is provided for driving the respective induction fans 13. The power for driving the actuator shaft 24A is not here 55 shown, but the shaft 24A carries gears and each of the shafts mounting the induction fans have co-acting gears that are adapted for being driven by the gears disposed upon the shaft 24A. While the form of mechanism 60 herein shown and described is admirably adapted to fulfill the objects primarily stated, it is to be understood that it is not intended to confine the invention to the one form of embodiment herein shown and described, as 65 it is susceptible of embodiment in various

forms, all coming within the scope of the claim which follows.

What I claim is:

In a device of the class described, in combination with a fruit drying chamber, a breeching vertically secured to the end of the chamber, said breeching divided into a plurality of compartments, an induction fan disposed within each of said compartments, and a roller rotatably disposed between the chamber and the breeching at their meeting edges, said roller having a fabric with a plurality of holes disposed therein.

FRANK D. ROBBINS.
